UNITED STATES PATENT OFFICE.

P. ELMENDORF SLOAN, OF SYRACUSE, NEW YORK.

IMPROVEMENT IN NEWSPAPER-FILES.

Specification forming part of Letters Patent No. 179,822, dated July 11, 1876; application filed June 3, 1876.

To all whom it may concern:

Be it known that I, PETER ELMENDORF SLOAN, of Syracuse, Onondaga county, State of New York, have invented an Improvement in Newspaper-Files, of which the following is a specification:

The nature of my invention consists in the construction of a paper-file for newspapers and the like in joints, so as to be readily read, while being held in hand, by doubling up in a way to bring any part of a large paper within easy range of the eyes without inconvenience to the reader.

The construction is as follows, referring to the accompanying drawing, in which Figure 1 is a side or profile view. Fig. 2 is a perspective view with the joints turned out of line.

The same references are used in both figures.

I employ three (more or less) pieces, A B C, the ends of which I prefer to have sufficiently broad to form a steady joint, that, while it readily allows the parts to swing around and double onto each other, holds them in the same plane, or nearly so. The parts may be united by any convenient hinge or lacing (two forms being shown at *a* and *b*) that will give to the parts flexibility. At the outer ends a plate or bar of metal, or other suitable material, D E, is affixed, running parallel with the bars, at a distance therefrom sufficient to introduce the papers between them.

When two, three, or more bars are used, the center ones, F, are jointed, by means of rings *e* or other suitable device, to the plates D E. Screws *s* pass through each of the plates near their ends, and enter the pieces A B C, into which they screw. There should be a countersink at each of the screw-holes, to facilitate the entrance of the screws when thrust through the paper, as hereafter described. A ring, *r*, is attached to each of the screws *s*, through which a rod, G, can be put when the parts are to be held in line.

The paper, when inserted between the plates and pieces A B, is held by the screws, which pass through it into the countersunk holes before named. The file can be hung up by its rings, either with or without the rod G.

Having thus described my improved paper-file, I claim as my invention—

1. A jointed paper-file, made in sections, united by suitable hinges or joints of flexibility, constructed and arranged substantially as and for the purposes herein described.

2. In combination with a jointed paper-file, as described, the ring-screws *s*, as and for the purposes specified.

3. The rod G, in combination with the jointed paper-file, substantially as and for the purposes herein set forth.

P. ELMENDORF SLOAN.
